UNITED STATES PATENT OFFICE.

GUSTAVE A. SCHEEFFER, OF INDIANAPOLIS, INDIANA, ASSIGNOR, BY MESNE ASSIGNMENTS, TO ROLLER SMITH CO., OF NEW YORK, N. Y., A CORPORATION OF NEW YORK.

ELECTRIC METER.

1,082,654.

Specification of Letters Patent.

Patented Dec. 30, 1913.

Application filed January 14, 1910, Serial No. 538,031. Renewed September 19, 1913. Serial No. 790,730.

To all whom it may concern:

Be it known that I, GUSTAVE A. SCHEEFFER, a citizen of the United States, residing at Indianapolis, in the county of Marion 5 and State of Indiana, have invented a certain new and useful Improvement in Electric Meters, of which the following is a full, clear, concise, and exact description, reference being had to the accompanying drawings, forming a part of this specification.

My invention relates to an improved form of electricity meter adapted to measure a quantity of electricity flowing through any given circuit.

My improved meter construction provides for accuracy of operation, ease of inspection and repair and durability of working parts.

My invention consists particularly in an improved form of lifting device for raising 20 the movable armature of a meter of the class described from its lower bearing, which is particularly to be desired in connection with shipping the meters. The lifting mechanism is operated by a screw 25 which, when it is desired to lift the armature, is turned in against the lifting member as far as a shoulder formed on the screw will permit, as a result of which no judgment need be exercised to determine whether 30 the armature has been properly lifted or not.

The several drawings illustrating my invention are as follows:

Figure 1 is a longitudinal sectional view 35 through the shaft 2 and shows the lifting device in a position to raise the armature shaft from its lower bearing. Fig. 2 is a detail view of the magnetic shield 20 showing the slot formed therein to permit the 40 insertion and removal of the armature shaft.

Similar numerals refer to similar parts throughout the several views.

As shown in the drawings, the base 1 supports the lower end of an armature shaft 2 by means of a lower bearing 3. The shaft 2 carries near its lower end a disk 5 of non-magnetic material disposed between the poles of a permanent magnet 6 held in proper position by the bracket 8 secured 45 to the base plate 1. Main supporting posts 18 extend outwardly from and are rigidly secured to the base plate 1 and by means of arms 19 support a magnetic shield 20 between the permanent magnet 6 and the meter windings.

The lower bearing 3 is secured to the base plate 1 by means of screws 84 one of which extends through the lower bent end of a flat spring 85, the upper end of which is slotted as indicated at 86 in Fig. 1 to pass around the armature shaft 2. The spring 85 is so formed that it normally rests below the hub 5^a of the disk 5 when the shaft 2 rests upon its lower bearing. A screw 87 is threaded through the lower bearing support 3 to engage the spring 85 to move it from its normal position upward to a position engaging the hub 5^a to raise the armature shaft 2 from its lower bearing so as to protect such lower bearing for purposes of shipping. 60 The screw 87 is provided with a shoulder 87^a so located that when the screw is turned through the lower bearing support 3 as far as it will go, the spring 85 is moved against the hub or collar 5^a with sufficient force to 65 positively prevent jar of the instrument in shipping from damaging the lower bearing of the shaft. In this position a collar 88 secured to the shaft 2 by means of a set screw as indicated and having a rounded upper end engages a countersunk opening 89 in the plate 20 which opening is somewhat larger than the slot 20^a formed in the upper portion of the plate 20 to permit the 70 insertion and removal of the armature shaft 2. As a result upward movement of the armature shaft is prevented beyond a certain point by the collar 88, and for this position of the parts the armature shaft is held in its 75 normal position even though the lower supporting bearing is removed.

The bearing support 3 has threaded therethrough a sleeve 56 adapted to receive at its upper end, the lower end of the armature shaft 2, a bearing 57, upon which the lower end of the shaft 2 rests is inserted in the lower end of the sleeve 56 and held in place by a spring 59 secured to the support 3 by a screw 60. A hole 62 is formed in the spring 59 to be engaged by a pin 61 secured in the support 3 when the spring 59 is in a position to hold the bearing 57 in place in the sleeve 56. While I have shown the detailed construction of this bearing in the present application, it is not claimed herein 80 as it forms the subject matter of a co-pending application, Serial No. 538,028 filed January 14, 1910.

While I have shown my armature lifting mechanism in the particular embodiment 85

herein described, I do not, however, limit myself to this exact construction but desire to claim any equivalent that may suggest itself to those skilled in the art.

5 What I claim is:

In an electric meter, the combination of a base, an armature shaft, a retarding disk carried by the shaft, a retarding magnet, a lower bearing for the shaft, a bracket for 10 supporting such bearing, a lifting spring normally out of engagement with the disk and shaft, a screw threaded through the bracket for engaging the spring to move it up against the disk to lift the shaft from its

lower bearing, an adjustable collar secured 15 to the shaft above the disk and conically shaped at its upper end, and a plate supported from the base and provided with an opening to receive and engage the upper end of the collar when the shaft is lifted 20 from its lower bearing.

In witness whereof, I hereunto subscribe my name this 28th day of December, A. D. 1909.

GUSTAVE A. SCHEEFFER.
